UNITED STATES PATENT OFFICE.

KARL G. GUSTAFSON, OF MULLAN, IDAHO.

CROSSCUT-SAW HANDLE.

1,252,105.

Specification of Letters Patent.

Patented Jan. 1, 1918.

Application filed March 6, 1917. Serial No. 152,650.

To all whom it may concern:

Be it known that I, KARL G. GUSTAFSON, a citizen of the United States, residing at Mullan, in the county of Shoshone and State of Idaho, have invented certain new and useful Improvements in Crosscut-Saw Handles, of which the following is a specification.

This invention relates to improvements in cross cut saw handles, which are intended to be detachably secured thereto and the embodiment of my invention involves the provision of a structure that will be rigidly secured to the end of a cross cut saw and which will not become loosened in its engagement therewith by use.

It is an object of my invention also to provide a detachable saw handle that may be quickly adjusted to the saw and which comprises a minimum of operating parts.

A still further object of the invention is the provision of a device of the above stated character which shall be simple in construction, durable in use and that may be manufactured and sold at a minimum cost.

With the above and other objects in view the invention consists in the novel features, details of construction and combination of parts which will be hereinafter more fully set forth and illustrated in the accompanying drawings and pointed out in the appended claims.

In the drawings:—

Figure 1 is a side view of my saw handle showing it attached to a portion of a cross cut saw.

Fig. 2 is a view looking from the rear and showing the nut lever at right angles therewith.

Fig. 3 is a cross section through Fig. 1.

Fig. 4 is a partial view of the clamping screw.

Referring specifically to the drawings in which like characters of reference indicate like parts throughout the several views the numeral 1 designates a saw handle with a squared lower portion 2 upon the face thereof that engages saw end 3. I provide a plate 4 with a central groove therein extending the entire length and provided to receive the end of the saw blade. Centrally of the plate and passing through the handle portion is a bore for receiving the clamping screw 5 which is provided with a hook 6 upon one end and threaded upon the opposite end. This clamping screw engages in

a hole 7 in the saw blade and is provided to hold the blade centrally of the handle. Upon the opposite end engaging the threaded portion is a nut 8 threadably engaged therewith and provided with an extended lever arm 9 comparatively thin and of metal that will spring easily in the hands of the operator. Upon the inner face at 10 of the lever is a pin and upon the handle to register therewith is a pin socket 11 which is intended to receive the pin 10 and retain the lever in set position and against displacement. To make the end of the lever readily taken hold of I provide on the lower end of the handle a cut out portion 12 which gives sufficient room for the fingers to get under the lever to withdraw the pin for removing the handle. Upon the back side of the squared portion of the handle I insert a plate 13 preferably of metal and provide a recess 14 of sufficient depth and size that it will receive the key lever when the same is disposed in the position shown in Fig. 2. This will allow a certain amount of slack between the handle and the saw blade and will allow the end 6 thereof to be disengaged from the saw blade.

When I again wish to engage the blade in the handle I insert the hooked end 6 of the clamping screw to the saw and turn the nut 8 with the lever downward and in so doing I take up the slack between the handle and the saw and closely engage the parts thereto. To provide this take-up I provide on opposite corners of the plate 13 a slight bevel 16 and as the lever is turned the edges will engage the bevel and dispose the lever in the position shown in Fig. 1. By means of the pin 10 and socket 11 I am enabled to maintain the key in a locked position and no amount of handling can possibly serve to loosen the handle with respect to the saw blade. Most handles are engaged to the saw blade by means of a thumb screw or like device which under vibration and use does not afford positive engagement between the saw blade and the handle and it is to overcome this objection that I have devised the construction herein shown.

From the foregoing description it will be apparent that I have provided an efficient organization for carrying out the objects of my invention and while I have particularly described elements which are adapted to perform the function set forth it is obvious that various changes therein and in minor

details of construction may be resorted to without departing from the spirit and scope of the invention as defined in and by the appended claims.

5 I claim:—

1. The combination with a saw blade of a detachable perforated handle and a screw engaging the blade and passed through the handle, a clamp nut on the screw, a yieldable lever integral with the nut, and a locking pin on said lever adapted to engage a socket on the handle.

10 2. The combination with a saw blade of

Copies of this patent may be obtained for five cents each, by addressing the "Commissioner of Patents, Washington, D. C."

a detachable handle, a grooved, perforated plate carried by the handle and engaging the saw, a clamping screw connected to the saw and passed through the grooved plate and handle, a second plate on the screw at the outside of the handle having beveled corners, a nut threaded on the screw and provided with a yieldable lever to engage said corners to take up slack, and means for locking said nut and lever.

15 In testimony whereof I affix my signature.

KARL G. GUSTAFSON.
